Morrill A. Shepard.

UNITED STATES PATENT OFFICE.

MORRILL A. SHEPARD, OF ORIO, ILLINOIS.

HYDRAULIC MOTOR.

Specification of Letters Patent No. 24,826, dated July 19, 1859.

To all whom it may concern:

Be it known that I, MORRILL A. SHEPARD, of Orio, in the county of Wabash and State of Illinois, have invented certain new and useful Improvements in the Method of Giving Motion to Water-Wheels, and that the following is a full, clear, and exact description of the same, reference being had to the accompanying drawings, forming a part of 5 this specification, in which—

Figure 1, is a vertical longitudinal section of my apparatus, and Fig. 2, is a vertical projection of the same.

Similar letters of reference, in each of the 15 several figures, indicate corresponding parts.

The nature of my invention consists in a method of giving motion to a water wheel (by means of which power may be applied to give motion to any machinery) without 20 the necessity for the formation of the dam as ordinarily employed for such purpose.

To enable others, skilled in the art, to make and use my invention, I will proceed to describe its construction and operation.

25 In the drawing, S, represents the stream in which is inserted the draft tube e, made air and water tight, the upper portion of said tube is constructed as shown in the drawing with the head h, and curved piece x, made for the reception of the water wheel a; b is the axis upon which the water wheel is hung and l, is a crank through which motion is given to the machinery desired to be operated by the water wheel. The joints 30 in the outer casing are made air-tight, by any well known means, and a water or other fluid jacket may be employed about the axis to prevent effectually the ingress of air.

t, t, are the buckets of the wheel. 40 At the upper part of the casing x, an opening k, is made into which the siphon c, is fitted so as to form an air tight joint.

m, is an opening in the head h, which may be closed at pleasure by an air tight joint.

45 The siphon c, is arranged as shown in the drawing, the upper part being connected with the air tight casing x, while the lower part of the siphon is inclosed by the tube d, made open at the top. The tube d, I would

state, may however be made air-tight if it is deemed expedient.

The tube d, forms a part of the tube T, which rests on the bottom of the stream, its opening O, being situated as shown, in the more elevated portion of the stream. 55

My apparatus is intended for running streams where the fountain head is necessarily higher than the point of discharge.

The operation of my invention may readily be understood. The draft pipe e, is 60 filled with water through the opening m, and the faucet f, is closed. The valves z, n, are then opened and the water is driven by its momentum and atmospheric pressure through the tube T; its egress through the 65 branch d, being prevented by the atmospheric pressure at its open top, the water is therefore forced up the siphon c, and on to the buckets b, of the wheel a; the latter being thus set in motion, will cause a partial 70 vacuum in the space in which the wheel rotates, the water being now let off from the draft tube by means of the faucet f, which is now open, a rapid motion will be given to the water wheel, and through it to any 75 machinery it may be desired to operate. A partial vacuum being created, as described in the draft tube, the water wheel will move with much less resistance than water wheels 80 employed in the ordinary manner. 80

An inclined pipe or tube may be employed, reaching from the casing x, down into the stream, somewhat similar to the tube used in the ordinary hydraulic ram, but this arrangement is expensive and inconvenient, 85 because the tube must be made much longer than in the plan shown, in order to obtain the necessary momentum.

I have represented one form of wheel only, and one method of operating the same in a 90 partial vacuum, but it is obvious that many other forms of wheels may be employed and their arrangement so as to work in a partial vacuum modified.

It is obvious that this invention may 95 be applied to the propulsion of a boat moving up stream, the opening O, of the tube T, being placed at the bow of

the boat. This application, however, may not be adopted and is simply adverted to in order to protect myself in the use of my invention with traveling as well as stationary machinery.

What I claim as my invention and desire to secure by Letters Patent, is—

The combination of the vacuum tube *e*, and tube *c*, for giving motion to the water

wheel by the action of an undammed stream, 10 substantially as herein described.

The above specification of my impt. in the application of the siphon as a motive agent signed by me this 25th day of May 1859.

MORRILL A. SHEPARD.
